(75) Inventor: **Mitchell H. Babkes**, Saugus, CA (US)

* cited by examiner

(73) Assignee: **Sylmark Holdings Limited**, Dublin (IE)

Primary Examiner—Freda Nunn

Assistant Examiner—Kevin K. Rudzinski

(74) *Attorney, Agent, or Firm*—Kathy Mojibi Kavcioglu

(**) Term: **14 Years**

(57) **CLAIM**

I claim the ornamental design for the combination step ladder, hand truck and dolly device, as shown and described.

DESCRIPTION

(21) Appl. No.: **29/206,625**
(22) Filed: **Jun. 2, 2004**
(51) **LOC (8) Cl.** 12-02
(52) **U.S. Cl.** **D34/14**
(58) **Field of Classification Search** D34/12-27;
182/16, 20, 102, 103, 127; 280/30, 47, 28,
280/37, 79, 11, 79, 3; 190/107, 103, 115, 127
See application file for complete search history.
